UNITED STATES PATENT OFFICE.

ANTON M. KROCKZEK, OF CHICAGO, ILLINOIS.

BIRD CAGE.

Application filed November 22, 1926. Serial No. 149,881.

This invention relates to bird cages and has for its primary object the provision of locking means between the cage proper and the base thereof.

5 Another object of the invention is the provision of a base and a tray disposed therewithin, and also means for locking said tray with the cage proper.

With the above general objects in view 10 and others that will appear as the nature of the invention is better understood, the same consists in the novel construction, combination and arrangement of parts hereinafter more fully described, illustrated in the accompanying drawing and pointed out in the 15 appended claims.

In the drawing forming a part of this application and in which like designating characters refer to corresponding parts throughout the several views,

Fig. 1 is a top plan view of the base and tray of the cage, with cage proper or dome partly removed;

Fig. 2 is a cross-sectional view through the 25 base and the tray and through a fraction of the dome or cage proper;

Fig. 3 is an enlarged view of one of the locking means associating with the tray for locking the dome thereto;

30 Fig. 4 is an enlarged cross-sectional view of one of the locking means showing the operation thereof; and

Fig. 5 is a view partly in elevation and partly in section taken on line 5—5 of Fig. 4.

35 Referring to the drawing there is shown therein a base generally indicated by 1 having a bowl-like portion 2 from which radiates a horizontal portion constituting shoulder 3 from which the annular upright portion 4 projects. From said annular upright portion 4 flange or rim 5 flares out on substantially horizontal plane. Cooperating with said base is a tray 6 having a curved portion 7 which is adapted to closely fit within the bowl-like portion 2 of base 1. Said tray further embodies a horizontal flange 8 which flares out from said curved portion 7 of the tray and is adapted to rest upon the shoulder 3 of the base.

50 The cage proper or dome embodies a plurality of wire strands 9 which are arranged in a round formation as is clearly apparent from Fig. 1. The lower ends of said wire strands 9 are held in position by annular band 10 wherein the wire strands 9 are frictionally held within loops 11 struck out

in said band. Said band is receivable within the annular upright portion 4 of the base 1 and normally is adapted to rest upon the flange 8 of the tray 6 upon shoulder 3 of 60 the base 1.

Flange 5 of base 1 adjacent the annular upright portion 4 thereof has a tongue 12 which is secured under said flange 5 by means of rivets 13. Said tongue passes 65 through said annular upright portion 4 adjacent said flange 5 and projects inwardly of the tray and overhangs shoulder 3 of base 1. Normally, when the dome is within the base said tongue overhangs the annular 70 band 10 and prevents its upright shifting with respect to the base. On a line diametrically opposite from said tongue 12 the base is provided with a shifting locking means 75 embodying lip 14 which passes through the slit 15 made in the upper edge of the annular upright portion 4 of base 1 and adjacent flange 5. Said lip is integrally formed with an arcuate plate 16 which normally rests upon and abuts the outer periphery of 80 said annular upright portion 4 and to which it is riveted by its other end as at 17. Said plate 16 adjacent its rivet point 17 is provided with a rigidly formed horizontal extension 18 which projects from the upper 85 edge of said plate 16. Normally said extension 18 abuts the lower face of flange 5 and by means of rivet 19 it is secured to said flange 5 for further holding plate 16 in 90 position. At its other termination and beyond lip 14 said plate 16 is further provided with an integrally formed L-shaped plate 20 constituting a hook by means of which plate 16 may be angularly shifted away from the annular upright portion 4 of the base 1. 95

It is observed that said plate 16 is of a resilient springy material by reason of which fact it closely abuts the outer periphery of the annular upright portion 4 and by reason of which fact lip 14 normally projects beyond the inner periphery of said annular upright portion 4 and overhangs annular band 10, flange 8 of tray 6 and shoulder 3 of base 1.

100 Radially in respect of the base 1 lip 14 has downwardly struck out rib 21 which frictionally engages the upper edge of annular band 10 for preventing shifting of the dome with respect to the base, which arrangement will also prevent rattling of the 105 several parts of the cage during transportation, as is clearly shown on Fig. 4. The up-

per edge of said annular upright portion 4 of base 1 at a point below said rib 21 is provided with slot 22 within which said rib 21 is accommodated and within which it is 5 adapted to make sliding movement when the lip 14 is shifted out of its normal position by means of handle 20.

To remove the dome from the base, plate 16 is manually shifted from annular upright 10 portion 4 by means of handle 20, which operation will withdraw lip 14 from its normal position best shown on Fig. 1 and will pass the same beyond the outer periphery of the annular upright portion 4. Then the 15 portion of band 10 with the dome adjacent said lip 14 may be raised for withdrawing the same from within said annular upright portion 4, flange 8 and shoulder 3 for removing the same from within the base as is 20 apparent. It is further observed that in the operative association of the dome with the base, tongue 12 and lip 14 remain within the respective adjacent pairs of wire strands 9, which arrangement prevents the rotary 25 shifting of the dome with respect to the base.

While there is described herein a preferred embodiment of the present invention, it is nevertheless to be understood that minor 30 changes may be made therein, without departing from the spirit and scope of the invention as claimed.

What I claim as new is:

1. Means for attaching a bird cage to its 35 base comprising a fixed fastener carried by the base and engaging the cage, and a catch device formed of spring metal and attached to the base at plural points at substantially right-angles to each other to distribute the 40 strain at the points of attachment to the base when the fastener is flexed, said fastener having a lip adapted to engage the bird cage to retain the same on the base.

2. Means for attaching a bird cage to its 45 base comprising an elongated spring metal

member having a lip and a horizontal extension formed adjacent to its ends and extending in opposite directions, said horizontal extension adapted to be attached to the cage base and said lip adapted to engage the bird cage to hold the same on the base, and an L-shaped extension on said member forming a handle for flexing the same to release said lip from the bird cage. 50

3. Means for attaching a bird cage to its 55 base comprising an elongated spring metal member having a pair of lips formed integrally therewith and located each adjacent an end of said member and bent to extend in opposite directions, one of said lips adapted to be attached to the cage base and the other lip adapted to engage the bird cage to hold the same on the base, an extension on said member forming a handle for flexing the same to release said latter named lip from the bird cage, and said last named lip formed with a rib constituting a centering device for the cage with respect to its base. 60

4. A bird cage comprising a base having a shoulder and a rim, a wire strand dome, 70 an annular band engaging the lower ends of the wire strands of said dome, a tongue upon said rim normally overhanging said annular band and being disposed between a pair of adjacent wire strands, a lip at substantially diametrically opposite point from said tongue in association with said rim, said lip normally overhanging said annular band and being disposed between a pair of adjacent wire strands, said rim at its base portion having a slit through which said lip is 75 adapted to shift, a downwardly projecting rib formed in said lip for frictionally engaging the upper edge of said annular band when said lip is in operative position, and means upon said lip for withdrawing the same from engagement with said annular band. 80

In testimony whereof I affix my signature.

ANTON M. KROČZEK.
